BREAKWATER

Richard E. Chadwick, Westmount, Quebec,
CanadaApplication April 20, 1933, Serial No. 666,982
In Canada April 8, 1933

13 Claims. (Cl. 61—4)

This invention relates to improvements in the construction and mode of installing breakwaters for the protection of completed or partially completed wharves, docks, piers, foundations, light-houses and other structures erected on the bed of a river or other body of water, or as a protective barrier in connection with vessel salvaging operations and similar work.

An object of this invention is to provide a breakwater of improved construction that may be easily installed as a temporary or permanent structure in places where strong tidal or other currents must be contended with and which, when installed for temporary use, may be readily freed from its weighting means and reclaimed for subsequent use in other locations.

Another object is to provide a breakwater comprising a preformed unitary frame of rigid construction designed to permit convenient handling thereof by conventional hoisting equipment when the frame is being installed or when it is being reclaimed after a period of temporary use.

Another object is to provide a breakwater comprising a unitary rigid frame structure of skeleton form presenting relatively large openings for the flow of water therethrough so that the frame may be grounded in place with less difficulty than is usually encountered in the presence of strong currents, the openings in the frame being subsequently closed by sheet piling or the like applied to the frame after it has been anchored in position.

A still further object is to provide various improved methods of weighting the breakwater that may be used selectively depending upon the design of the frame structure and the conditions under which it is installed.

Other objects, characteristic features and advantages of this invention, as well as the preferred details of construction, will be developed in the following description taken in connection with the accompanying drawings, in which—

Fig. 1 is a top plan view of a breakwater constructed and installed in accordance with this invention.

Fig. 2 is a view in side elevation of the breakwater frame as it appears without the sheet piling which is applied to close off the flow openings through the frame after the latter has been installed.

Fig. 3 is a sectional view taken substantially along the line 3—3 of Fig. 2.

Fig. 4 is a sectional view taken substantially along the line 4—4 of Fig. 1.

Fig. 5 is a top plan view illustrating a modified

form of leg structure for supporting the frame of the breakwater.

The frame structure of the breakwater provided in accordance with this invention comprises spaced vertical members 5, 5a and 5b constituting supporting legs rigidly connected to each other by openwork bracing generally indicated at 6 in Figs. 1 and 2. This openwork bracing provides, between the several legs, openings of considerable area which are left clear for the flow of water therethrough during installation of the frame so that, in the presence of strong currents, such installation is more easily accomplished than would be the case if the open spaces between the legs were of negligible area or completely closed off. Generally speaking, the frame structure may include any desired number of supporting legs of hollow or solid construction and of any desired shape. These legs may also be made in one continuous length as shown herein or they may be composed of sections assembled one upon the other. In the construction shown in the present drawings the frame comprises three supporting legs consisting of hollow vertical cylinders arranged in triangular formation, the cylinder 5 being at the apex of the triangle and of somewhat greater diameter than the two remaining cylinders 5a and 5b. Each of these legs or cylinders is provided at the down stream side with an attached casing 7 which, when filled with concrete, as indicated at 8, constitutes a rigid backing that reinforces the cylinder against the pressure of the current, besides affording a stream line effect eliminating the formation of eddies.

The system of bracing connecting the supporting legs of the frame structure may be varied according to the size of the frame, the number and arrangement of the supporting legs and the conditions under which the frame is to be installed. As here shown the bracing connecting the supporting leg 5 with the remaining legs 5a and 5b comprises, in each instance, three vertically spaced horizontal connecting members indicated at A, B and C. The member A comprises two laterally spaced channels 9 having their ends fastened to the leg carried flanges 10 and 11, and their upper flanges connected by a top plate 12 which closes the opening between them. Each of the members B and C comprises a pair of upper laterally spaced angles 14 and a pair of lower similarly spaced angles 15 terminally attached to the leg carried flanges 16 and 17. Preferably, the upper and lower angles 14 and 15 at one side of the members B and C are connected to the opposing upper

and lower angles by horizontal connecting plates 18.

The horizontal members A, B and C have their central portions tied together by four vertical angles 19, 20, 21 and 22 fastened to the channels 9 of member A and to the horizontally extending angles 14 and 15 of members B and C. The vertical angles 19 and 20 are connected to the companion vertical angles 21 and 22 by connecting plates indicated at 24, 25, 26 and 27, the outer ends of the plates 25 being projected somewhat beyond the angles 19 and 20 and connected together by a bolt 28 carrying an eye 29 to which hoisting cables 30 may be attached for the purpose of lowering or raising the frame during installation or reclaiming operations. The horizontal connecting members A, B and C may also be tied together by suitable diagonal bracing such as that generally indicated at 32.

20 The bracing provided between the supporting legs 5a and 5b is shown to advantage in Figs. 1 and 4. It comprises three vertically spaced horizontally extending connecting members indicated at D, E and F. The member D is in the form of a channel having its ends connected to the legs 5a and 5b. The members E and F are in the form of I-beams having their ends connected to the legs 5a and 5b and their central portions connected to each other and to the member D by the vertical I-beams indicated at G and H.

Additional bracing for the upper portion of the frame structure may be provided in the form of a series of I-beams J connected between the channel member D and an I-beam K, the latter having its ends connected to the upper ends of the vertical angles 21 and its intermediate portion connected by a short I-beam L with the reinforcing casing 7 of the supporting leg 5.

40 In Fig. 1 the triangular frame is shown grounded at the upstream side of the protected structure which is indicated at O. The frame is lowered to this position with the aid of any suitable hoisting equipment to which the eyes 29 of the frame are attached by suitable cables such as those indicated at 30. The frame is then weighted in place by a number of removable rings 35 placed in each of the cylinders 5, 5a and 5b, said rings being supported by annular flanges 36 attached to the lower portions of the legs. Due to the size of the cylinder 5 and the weighting rings placed therein compared with the remaining cylinders and weighting rings sufficient weight is concentrated at the apex of the frame to resist overturning of the frame in the direction of the structure O which it protects. After the frame has been weighted in place the openwork bracing at each side of the cylinder 5 is closed off to provide inclined surfaces for deflecting the current away from the protected structure. This may be accomplished in various ways but I prefer to employ the steel sheet piling shown in Fig. 1, since sections of this piling can be conveniently slid into place from a position above the weighted frame. The sheet piling used in this connection is of well known construction. It comprises a plurality of sections 38 having their longitudinal edges slidably interlocked as at 38a so that these sections may be readily applied or removed by relative sliding movement in their lengthwise direction, the terminal sections of the piling at each side of the frame being preferably welded or otherwise fastened to the cylinders 5, 5a and 5b as indicated at 39. While this type of piling has been

found particularly useful because of the ease with which it may be applied or removed it may, if desired, be replaced by boarding, concrete slabs or any other suitable means for closing off the openings through the bracing at opposite sides of the cylinder 5. If it is desired to close off the three sides of the frame the sheet piling, boarding or slabs may also be applied to cover the bracing connecting the cylinders 5a and 5b as well as to the bracing connecting these cylinders with the cylinder 5.

80 Instead of being made in the form of sheet metal cylinders, each of the legs 5, 5a and 5b may, as shown in Fig. 5, consist of a cage-like tubular structure comprising a circular series of vertical steel or other members 40 bound together in column formation by hooping 41. In this case the supporting flange 42 for the weight rings 35 is welded or otherwise secured to the lower portion of the vertical members 40. Various other forms of hollow legs may also be employed in place of those mentioned herein.

90 Instead of using the weighting rings 35 various other methods of weighting the frame in place may be resorted to. For example, the hollow legs 100 of the frame may be filled with materials such as concrete, sand, stone, gravel, or cement or they may be weighted down by placing therein heavy objects such as steel rails or the like.

95 When the cylinders are weighted with concrete or with cement mixed with sand, stone or gravel, provision may be made in various ways for spilling a portion of the weighting material through the lower end of one or more of the legs whenever it is necessary to build up an artificial foundation 110 beneath the legs to compensate for variations in the contour of the natural foundation. Various expedients may be resorted to in connection with the spilling of the weighting material through the lower ends of the legs. Each leg may 115 be provided at its lower end with a support for the weighting material in the form of a downwardly opening door that is opened or permitted to open when conditions arise where it is necessary to permit a certain amount of the material 120 to be spilled through the doorway to build up a mound or artificial foundation. As an alternative to this, each leg could be provided at its lower end with a support for the weighting material in the form of a relatively thin bottom wall which 125 could be readily punctured whenever it is necessary to resort to spilling of the weighting material through the lower end of the leg.

130 In connection with the weighting rings 35 it may be further explained that the central openings of these rings provide a passage down through the centre of each leg for the introduction of material intended to be spilled through the bottom of the leg when this is necessary to build up an artificial foundation. Another advantage 135 incident to the use of these weighting rings is that spuds or piles having pointed lower ends may be passed downwardly through the openings in the rings and the pointed ends driven into the foundation below the leg to anchor the latter 140 against lateral displacement.

Having thus fully described what I now consider to be the preferred embodiment of this invention it will be understood that various modifications and desirable changes may be resorted 145 to within the scope and spirit of the appended claims.

Having thus described my invention, what I claim is:—

1. A breakwater comprising a frame including

- three widely spaced, hollow supporting legs arranged in triangular formation and rigidly interconnected by openwork bracing leaving flow openings of substantial area between the legs, and detachable members connected across the spaces between the legs to provide removable closures for said openings. 5 80
2. A breakwater including a unitary skeleton frame structure comprising three widely spaced vertical supporting legs rigidly connected to each other by openwork bracing to provide a triangular structure the corners of which are formed by the legs and the sides of which are formed by the bracing, members detachably connected between said legs to form a removable barrier to the flow of water between the legs, and means for weighting the legs in place, the diameter of one of said legs being greater than that of the two remaining legs. 10 85
- 15 3. A breakwater comprising a frame structure including hollow supporting legs rigidly attached to each other by openwork bracing, an annular supporting flange located in the lower portion of each leg and a plurality of centrally apertured ring-shaped weighting members arranged one upon the other on top of said flange. 20 90
- 25 4. A breakwater or deflector comprising three widely spaced vertical supporting legs interconnected by openwork bracing to form a triangular frame structure, the corners of which are formed by said legs. 30 95
- 35 5. A breakwater or deflector as claimed in claim 4 including ring-shaped weighting members removably supported within each of said legs, one of said legs and the weighting members therein being larger in diameter than the remaining legs and weighting members. 100
- 40 6. A breakwater comprising a frame including three widely spaced supporting legs arranged in triangular formation and rigidly interconnected by openwork bracing leaving flow openings of substantial area between the legs, said legs being of hollow tubular construction and the leg at the apex of the frame being larger in diameter than the two remaining legs. 105
- 45 7. A breakwater comprising a frame including widely spaced supporting legs arranged in triangular formation, bracing connecting each leg with the two companion legs and forming the three sides of the frame, the corners of which are formed by said legs, and additional bracing connecting the bracing at each side of the frame with the bracing at the two remaining sides. 110
- 50 8. A breakwater comprising a frame including 115
- 55 12. A breakwater comprising a frame structure including three widely spaced supporting legs arranged in triangular formation and rigidly connected to each other by openwork bracing, said legs being of hollow construction to receive reinforcing and weighting material, and plate members attached to the rear side of each leg to form a triangular casing also adapted to receive reinforcing and weighting material. 120
- 60 13. A breakwater comprising three widely spaced supporting legs arranged in triangular formation and interconnected by openwork bracing to form a rigid triangular frame adapted to be grounded with the apex directed upstream, said openwork bracing leaving flow openings of a considerable area between the legs to reduce the pressure on the frame during grounding thereof, and means for closing off the front openings of the frame at each side of the apex thereof subsequent to the grounding of the frame, said means comprising members detachably connected to the legs to span the spaces between the legs at the apex of the frame and the legs at the two remaining corners of the frame. 125
- 65 130
- 70 135
- 75 140
- 80 145
- 85 150
